WILLIAM K. BASSFORD, OF PERTH AMBOY, NEW JERSEY.

EXPLOSIVE-ENGINE.

1,105,017.

Specification of Letters Patent.

Patented July 28, 1914.

Application filed July 5, 1912. Serial No. 707,683.

To all whom it may concern:

Be it known that I, WILLIAM K. BASSFORD, a citizen of the United States, and a resident of Perth Amboy, county of Middlesex, and State of New Jersey, have invented certain new and useful Improvements in Explosive-Engines, of which the following is a specification.

This invention relates to improvements in explosive engines of that class wherein hydrocarbon or other suitable volatile fuel such as gasolene, kerosene, crude oil, alcohol, may be used.

In a more specific way it may be stated that the present invention relates to and aims to provide a practical organization of the engine and fuel supply system wherein liquid fuels of different specific qualities, such as gasolene and kerosene, for example, may be employed, and the supply and temperature of the same as fed to the engine properly regulated.

I have found by long experiment that it requires a certain amount of air passing through an aperture in which is inserted a fuel nozzle to properly atomize the fuel; that it requires a certain amount of heat to raise the temperature of this atomized fuel to a certain predetermined degree and that the proper way to keep this heated atomized fuel at said temperature is to use an indicator in the heated atomized fuel as it passes to the engine to indicate to the operator at once the correct temperature of the fuel and the possible necessity of regulating the heat of the fuel. I lay particular stress on the indicator being placed in the heated atomized fuel, for the reason that it is the temperature of this fuel that should be kept at the proper point.

It is well known that fuels of different specific gravities require different temperatures for vaporization and by the present invention means are provided for heating the atomized fuel, for controlling the heat and for indicating to the operator the temperature of the fuel being supplied to the engine so that he may operate said heat controlling means, and, if desired or required, change from one fuel to the other.

One of the objects of the invention is to provide such an apparatus as will indicate to the operator the temperature of the fuel being supplied to the engine so that the operator may govern the temperature of the fuel, and may in certain cases, change from

one fuel to the other, thereby enabling him to intelligently and practically use hydrocarbons of different specific gravities.

Other objects will appear from the hereinafter description.

One embodiment of the invention is illustrated in the accompanying drawings, in which the same reference character indicates the same part in the several views.

Referring to the drawings: Figure 1 is a side elevation of the invention, certain parts being shown in section. Fig. 2 is a detail view of one end of the heater shown in Fig. 1. Fig. 3 is a view of a modified construction of certain of the elements shown in Fig. 1. Fig. 4 is a view of still another modification.

Referring specifically to Figs. 1 and 2 of the drawing, the part marked A represents the engine and B an exhaust pipe leading therefrom to the outer end of which is connected one end of the heater C. Extending through the other end of the heater, and near the outlet end of the exhaust pipe C, is another exhaust pipe D, having a damper or valve E, preferably near the inner end thereof, and provided between the chamber and the end of the heater with a series of perforations d. The shaft e of the valve E extends outside of the heater, and is provided with an operating handle F, carrying the locking lever f, which engages the ratchet f' to hold the damper in a set position. G is a coil of pipe inside the heater, and between the coils may be arranged a series of perforated baffles, P. To the end g of this coil, G, is connected a carbureter J, which is connected by a pipe K to a kerosene supply. The supply of kerosene fed to the carbureter is governed by the needle valve j, the nozzle end of which extends into the air inlet pipe g', which is connected to the pipe g. To the other end, g² of the coil G is connected the pipe Q, which leads to the engine, and through which the atomized heated fuel is supplied to the same. Connected to this supply pipe Q is another carbureter, M, which is connected by the pipe N to the gasolene supply, which is governed by the needle valve m. O is an auxiliary air supply valve located in the pipe Q, adjacent to the carbureter. Located in the pipe Q, and preferably between the carbureter M and the heater G, although it may be located in the heater itself, is an indicator, 10, which may be a mercurial ther-

mometer, 11, provided with graduations, 12, to indicate the temperature of the fuel, air or gas passing through the pipe Q. The face of this thermometer is marked preferably in three places by the letters H, T and L, the first and last to indicate the two extreme temperatures, and the intermediate one (T) to indicate the working temperature of the apparatus. The thermometer 15 may be provided with adjustable pointers, 13, 14 and 15, marked respectively H, T and L, to indicate the temperatures on which the apparatus is to operate. By using the adjustable pointers so marked, the extreme temperatures may be adjusted as desired, and depending somewhat upon the 20 grade and character of fuels used.

The operation of the apparatus is as follows: The valve E is turned crosswise of 25 the pipe B to the dotted line position shown in Fig. 1, and held in that position by the locking lever f, carried by the operating handle F. The engine is now started on 30 gasoline by opening the needle valve M, the exhaust from the engine passing out of the pipe B, with the valve E in the said dotted line position, will circulate through the perforated baffle P, around the coil G, through 35 the perforations b into the pipe B, and out through the end of the said pipe, causing the 40 temperature of the air entering through the pipe g', and passing through the coil G, to quickly rise. When the temperature of the air as it passes through the pipe Q, reaches 45 the point H, marked on the indicator 10, kerosene is supplied by opening the valve j, and gasoline is cut off by closing the needle valve m. If the temperature indicated remains at the point H, the operator turns the 50 valve E to the full-line position shown in Fig. 1, so that the exhaust will pass directly through the pipe D. The temperature of the kerosene should now fall slightly; but so long as it remains approximately at the 55 intermediate temperature, (T) the engine will operate on kerosene, and the operator is not required to change the condition of the heater, but permits the engine to operate with the exhaust, passing out directly 60 through the pipe D. When the engine is operating under said conditions, should the temperature of the kerosene passing through Q fall approximately to the point marked L, the operator will turn the valve E cross- 65 wise of the pipe, as hereinabove referred to, by operating the handle or lever F, whereupon the exhaust through B is caused to circulate around the coil G and through the 70 perforations d, and out of the pipe D, the temperature of the kerosene passing through Q should now rise, and when the temperature reaches or begins to reach the temperature indicated by H, the valve E is again 75 operated by the operator as hereinbefore described. Should, however, when the op-

erator closes the valve E the temperature of the kerosene fuel passing through the pipe Q continue to lower, and reaches the point L, the operator turns on the supply of gasoline by opening the needle valve m, and cuts off the kerosene supply by closing the valve j, and operates the engine on gasoline until the temperature of the air passing through the pipe Q rises to the temperature indicated by H, when kerosene can be again turned on and gasoline turned off, and the valve E operated as required under the conditions hereinabove described.

By the apparatus just described, the operator has before him an indicator which at all times will indicate to him the exact temperature of the fuel passing through the pipe Q and being supplied to the engine, whereby he can govern the said temperature as required, or change from one fuel to the other as the said temperature justifies.

In Fig. 3 I have shown a modified construction of the indicator. In this case I place in the pipe Q an ordinary two-legged thermostat, 20, and locate adjacent to the same a scale, 21, properly graduated and prominently marked with the letters H, T and L as hereinabove referred to.

In Fig. 4 I have shown another form of indicator, 30, which may have a face or dial, 31, properly graduated and marked prominently with the letters H, T and L, and provided with a finger or pointer, 36, which will point to the temperature of the fuel passing through the pipe Q; and when the pointer is at the parts marked H, T or L, the operator will know whether or not to change the direction of the exhaust, or to change from one fuel to another. In some cases the indicator may not be conveniently located where the operator can observe it. In this case, the wires 22, 23, 24 and 25 may be connected to the indicator as shown in Fig. 3, and lead to a battery and to an annunciator, or bell alarm, not shown, so that when the temperature of the fuel passing through the pipe Q reaches either one of the points H, L or T, the operator's attention is called to the same and he may manipulate the apparatus according to the required indication as hereinbefore stated. In Fig. 4 I have shown the wires 32, 33 and 34 connected to the indicator and lead to the battery, and an alarm, not shown, for the same purpose.

Having now described my invention, what I claim as new and desire to secure by Letters Patent is:

1. In a device of the class described, an internal combustion engine, a heater, a fuel-conductor within the heater, a liquid fuel supply connected to one end of the fuel conductor, a pipe connected to the other end of the fuel conductor and extending to the engine, a carbureter connected to the latter pipe, an indicator connected to the latter pipe be-

5 tween the engine and the heater for indicating the temperature of the fuel passing therethrough, an exhaust pipe leading from the engine to the heater to conduct the exhaust gases of the engine to the heater, a conductor for the exhaust gases leading from the heater, and a valve operatively related to the last-named conductor to cause the course of travel of the exhaust gases to be varied.

10 2. In a device of the class described, an internal combustion engine, an exhaust pipe leading therefrom, a heater connected to the exhaust pipe, another pipe extending into 15 the heater, said pipes being operatively related to the heater and each other to provide different courses of travel of the exhaust gases within the heater, a valve for controlling said courses of the exhaust gases, a coil 20 inside of the heater, a carbureter connected to one end of the coil to supply a fluid fuel through said coil, a pipe connected to the other end of the coil and extending to the engine, and an indicator connected to 25 the latter pipe, said indicator graduated or marked to indicate the temperature of the heated fluid passing through said pipe, whereby the operator may at the indicated 30 temperature operate said valve as and for the purpose set forth.

3. In a device of the class described, an internal combustion engine, an exhaust pipe leading therefrom, a heater having one end thereof connected to the free end of said 35 exhaust pipe, another pipe extending into said heater and having a valve therein, a coil inside of said heater and surrounding said pipe, a carbureter connected to one end of said pipe, said carbureter being connected to a 40 source of supply of liquid fuel of a certain specific gravity, a pipe connected to the other end of the coil and extending to the engine, a carbureter in said pipe, said carbureter being connected to a liquid fuel supply of different specific 45 gravity from the first fuel supply, an indicator in said pipe between the heater and the second mentioned carbureter, said indicator being graduated and marked to indicate various 50 temperatures of the fuel passing through said pipe whereby at a predetermined temperature the operator may operate the said valve and also operate the carbureters to change from one to another fuel as desired.

55 4. In a device of the class described, an internal combustion engine, an exhaust pipe leading therefrom, a heater having one end thereof connected to the exhaust pipe, a pipe extending through the other end of the 60 heater with its inner end adjacent to the outlet end of said exhaust pipe, a valve in the latter pipe, said pipe having a series of perforations in that part within the heater, a coil in the heater and surrounding said 65 latter pipe, an operating handle connected

to the valve whereby the valve can be turned to permit the exhaust to pass directly through the pipe, or turned crosswise of the pipe to cause the exhaust to pass around the coils and through the perforations and out 70 of the latter pipe, a carbureter connected to one end of the coil, said carbureter being connected to the kerosene supply, a valve in the carbureter to govern the supply of kerosene, a pipe connected to the other end of the coil and supplying fuel to the engine, a carbureter in said supply pipe, said carbureter being connected to a gasolene supply, a valve in the carbureter to govern said supply, an indicator in the supply pipe between 80 the heater and the last mentioned carbureter, said indicator consisting of a thermometer or thermostat having marks thereon to indicate a high, low and intermediate temperature, and adjustable pointers connected to said indicator and forming a part thereof, whereby the operator can observe the temperature of the fluid passing through the said pipe, operate the valve and turn on and govern the fuel supply according to 85 the temperature indicated, as and for the purpose set forth.

5. In a device of the class described, an internal combustion engine, an exhaust pipe leading therefrom, a heater having one end 90 thereof connected to the exhaust pipe, a pipe extending through the other end of the heater with its inner end adjacent to the outlet end of said exhaust pipe, a valve in the latter pipe, said pipe having a series of 95 perforations in that part within the heater, a coil in the heater and surrounding said latter pipe, an operating handle connected to the valve whereby the valve can be turned to permit the exhaust to pass directly 100 through the pipe, or turned crosswise of the pipe to cause the exhaust to pass around the coils and through the perforations and out of the latter pipe, a carbureter connected to one end of the coil, said carbureter being connected to the kerosene supply, a valve in the carbureter to govern the supply of kerosene, a pipe connected to the other end of the coil and supplying fuel to the engine, a carbureter in said supply pipe, said carbureter being connected to a gasolene supply, a valve in the carbureter to govern said 105 supply, an indicator in the supply pipe between the heater and the last mentioned carbureter, said indicator consisting of a thermometer or thermostat having marks thereon to indicate a high, low and intermediate 110 temperature, adjustable pointers connected to said indicator and forming a part thereof, whereby the operator can observe the temperature of the fluid passing through the said pipe, operate the valve and turn on and govern the fuel supply according to the temperature indicated, and a series of wires 115 connected to said indicator and adapted to 120

125 130

be connected to an alarm or annunciator, as and for the purpose set forth.

6. In a device of the class described, an internal combustion engine, an exhaust pipe leading therefrom, a heater connected to the exhaust pipe, a fuel-conveying pipe extending through the heater, means for changing the direction of the passage of the exhaust through the heater and around the fuel-conveying pipe, a liquid fuel supply connected to one end of said pipe, the other end of the pipe being connected to the engine, through which heated fuel is supplied to the engine, another fuel supply connected to said pipe 10 between the engine and heater, an indicator

extending into the pipe and into the path of which heated fuel is supplied to the engine said indicator being marked to indicate predetermined temperatures, whereby the operator may observe said temperature and change the direction of the exhaust in the heater and regulate the fuel supply to the engine. 20

In witness whereof I have hereunto set my hand at the city, county and State of 25 New York, this 27th day of June, 1912.

WILLIAM K. BASSFORD.
